CANDLE MAKING APPARATUS

Carl J. Schroeder, Chicago, Ill., assignor to
Standard Oil Company, Chicago, Ill., a corpora-
tion of Indiana

Application August 26, 1931, Serial No. 559,352

8 Claims. (Cl. 18—27)

This invention relates to candle making and it pertains more particularly to an improved method and means for making dipped candles.

In large production work candles are usually made by a casting process, the molten wax being poured into a mold around the wick, excess wax being removed and the candles being exuded from the molds and cut from the wicks preparatory to the casting of more candles. Candles of this type are limited to shapes which can be forced out of a mold. Hand dipped candles are formed by immersing the wick in the wax, removing it, allowing the adhering wax to harden and repeating this cycle to build up a candle of desired thickness. Dipped candles are usually slightly tapered, their shape being dependent on the rate at which the wicks are immersed in and removed from the liquid wax. Hand dipped candles have a more attractive appearance because of their wavy contour and their satin finish, each candle being slightly different from every other candle. Furthermore, hand dipped candles burn more evenly than cast candles because the wax mixture is more uniformly distributed and there is less chance for one side of the crater to melt and spill the wax down the side of the candle. Hand dipping makes it possible for a candle to have a relatively soft core and a harder exterior or shell and it also makes it possible to obtain desirable color effects.

The object of my invention is to provide an improved method and apparatus for dipping candles whereby production costs will be reduced to a minimum, speed of production will be increased, and the quality and appearance of the finished candle will be markedly improved. A further object is to provide a system which will require a minimum amount of effort for handling and which will yield a uniform product.

In order to carry out my invention I have provided an improved wheel which is rotatable on a vertical axis and which carries reciprocably movable track sections. These sections are radially disposed, and they are adapted to receive frame supporting carriages. A series of wax baths and hot plates are positioned around the central axis under the reciprocable track sections and the track sections are counterweighted so that they may be raised or lowered with a minimum amount of effort. By means of suitable turn tables I connect each wheel with a track on which the frame supporting carriages may be moved over other baths, hot plates, and/or tapering plates, and whereby the frames may be finally positioned adjacent packing

tables. A clearer understanding of the invention and the various features thereof will be understood from the following description taken in connection with the accompanying drawings wherein I have illustrated a preferred embodiment thereof.

In the drawings wherein similar parts are designated by like reference characters throughout the several views—

Figure 1 is an elevation of my improved dipping wheel showing in elevational section one of the tanks and one of the hot plates thereunder.

Figure 2 is an illustration in perspective of my candle carrying frame.

Figure 3 is a perspective view of the top of 15 the hot plate.

Figure 4 is a horizontal layout plan showing the relation of the wheels to the track system and of the track system to the packing tables.

Figure 5 is a top view of the butt tapering 20 plate.

Figure 6 is a vertical section taken along the lines 6—6 of Figure 5.

Figure 7 is a detailed elevation of the candle holding clip, and

Figure 8 is a section through the track showing the mounting of the frame-supporting carriage therein.

Referring to Figure 1, a vertical shaft 10 is journaled in a thrust bearing 11 on the floor and a bearing 12 on the ceiling. Radially extending arms 13 are braced or supported by tie rods or tension members 14 and they are held in spaced radial positions by spacer rods 15. At the end of each radial arm 13 I provide a block 16 carrying pulley 17, at an inner point of the arm I provide a block 18 carrying pulley 19 and adjacent the central shaft 10 I provide a block 20 carrying pulleys 21 and 22. A rope or cable 23 is connected at one end to track section 24, and it is trained over pulleys 17 and 21 to counterweight 25, thence over pulleys 22 and 19 to the other end of the track section. It will thus be seen that the track section 24 may be raised or lowered; it is guided by guide rod 26 which cooperates with an opening in a plate 26a on the track section. The track section is limited in its upward movement by contact of plate 26a with stop member 26b, this stop member being placed at such an elevation that the track section 24 will register with the turntable switch which will be hereinafter described.

Candle wicks are held in clamps 27 which are closely spaced on rods 28, the rods being held in notches 29 of channeled end sections 30, which

are secured by bars 31 to the ends of handle rod 32, and which are held in position by means of braces 33.

The supporting rod 32 is connected by means 5 of bolts 34 to carriages 35 which may be briefly described as a yoke on which two pairs of wheels are pivoted by means of journals 37 and stub shafts 38. The track section 24 substantially encloses the carriage wheels by means of downwardly extending flanges 39 and curved bottom flanges 40 on which wheels 36 are adapted to run.

At spaced intervals around the central shaft and under the reciprocable track sections 24 and candle carrying frames I mount wax baths and 15 hot plates. The wax 41 which may be a mixture of paraffin wax with stearine or stearic acid, is held in a deep rectangular receptacle 42 enclosed in an insulated outer shell 43 with a steam jacket 44 between the receptacle and the shell.

20 The hot plate 45 is supported by frame 46. The top surface of the plate may be doubly serrated or, in other words, it may consist of small points 47 with wax channels between them in two directions. Around the doubly serrated top I provide channel 48 which is connected by suitable bores to the hopper 49 from which wax may be withdrawn by pipe 50 and reintroduced into one of the dipping baths.

The wheels as above described are mounted 30 along the side of an endless track 51 which moves around the packing tables 52. Turntables 53 are provided with arcuate sections 54 and straight sections 55 so that the frame supporting carriages may be moved from track 51 to one of the 35 track sections 24 on a rotatable wheel, transferred from the wheel back to the endless track, or passed directly along the endless track. It is understood, of course, that suitable aligning means, such as pivoted channel sections, may be 40 used to hold the turntable wheel and endless track sections in fixed position with respect to each other when a frame supporting carriage is transferred. Likewise I provide locking means which are preferably counterweighed levers for 45 intercepting the path of the track when it is opened by rotation of the turntable or of the wheel. In other words, by suitable pins or gravity actuated locking means I prevent the carriages from rolling from the end of the track sections. 50 Under the endless track 51 I may provide other dipping baths 56 and the track sections above these baths may be reciprocably mounted and counterweighed as above described or in any other suitable manner. I also provide a butt 55 taper plate 57 which is a steam heated plate consisting of spaced holes 58 having tapered sides 59, said holes being connected by small bores 60 to the wax collecting hopper 61. A small hopper 62 surrounds this plate to catch any wax which may 60 run over the edge, and directs it through small bores to the hopper 61. The wax from this hopper may be discharged through pipe 63 to one of the dipping baths.

The operation of my invention may be described 65 as follows: Wicks from a plurality of spools are drawn through a wax bath, held straight while the wax is allowed to cool, and cut into candle lengths. The relatively stiff waxed wicks are individually secured to clamps 27, these clamps 70 are spaced along rods 28, and the rods are positioned in notches 29 of channel support 30. The frames are then hooked onto the carriages on track 51 and the carriages are transferred therefrom by one of the turntables 53 to one of the dipping wheels. The carriage is positioned above

one of the dipping baths of wax 41 and the frame together with track section 24 is lowered to dip the wicks in the bath. Counterweight 25 lifts the wicks out of the wax bath and holds them above the bath until the increment of wax which has adhered thereto is solidified.

The frame is again reciprocated to immerse the wicks in the wax bath and they are again allowed to cool before adding another increment of wax to the candle. In this manner the candle is built 10 up to any desired diameter.

As the dipping process proceeds it may be desirable to increase the hardness of the wax on the outer shells so that there will be no tendency 15 for the candles to spill wax down the sides thereof when they are burned. The wheel may be rotated in a clockwise direction and each succeeding bath may have a higher melting point wax or a harder wax than was contained in the preceding bath. Likewise, each succeeding bath may have 20 a slightly different composition and/or color.

As the dipping process continues an objectionable accumulation of wax forms at the base of each candle resembling an icicle or stalactite. Therefore, at intervals I lower the track section 25 and carrier therefrom until the end of the wick just touches one of the hot plates. If the surface of the hot plate were flat there would be a tendency for the candles to slide in a sidewise direction, but I have discovered that when the surface 30 is double serrated and the candles are slowly lowered the wax may be melted as fast as the candle is lowered and there is no tendency for the candles to slip.

When the candle is built up to the desired size 35 the carriage-frame unit is transferred from the wheel to the endless track 51. These candles may have a finishing dip in one of the baths 56 and finally they may be tapered at their base on the butt taper plate 57. As the candles are lowered onto this plate they are directed (by suitable extraneous means, if desired) into holes 58. The tapered surface 59 melts wax from the edge 40 of the candle and each of the candles is therefore shaped at its base and made exactly the 45 same length as the other candles.

The endless track 51 is built around a series 50 of packing tables 52 so that when the candles are finished the whole frame may be lifted from the carriage supports and operators may remove 55 the candles, roll them in wax paper, protect them by suitable cardboard rings or tubes and place them in cartons for shipping.

By using the above method and apparatus I 55 may dip 12 dozen candles from a single frame and may manipulate the frames in a rapid and convenient manner to produce hand dipped candles on a mass production scale with a minimum amount of labor and equipment. The candles are quite uniform in size and appearance; yet 60 they have that individual fineness and richness that distinguishes hand dipped candles from cast candles.

It is important in the dipping process that 65 drafts be avoided, because during the first dipping processes the candle wicks are easily bent. Cooling currents, if used, should be directed from above each of the frames, and if such currents are used the frame should be surrounded with a hood so that there will be no lateral motion 70 of the cooling current which might cause a bending of the candle wicks.

While I have described in detail a preferred 75 embodiment of my invention it is understood that I do not limit myself to any of the details

above set forth except as defined by the following claims.

I claim:

1. In apparatus of the class described, a wheel 5 rotatable on a vertical axis, radially extending arms on said wheel, a pulley on the outer end of each arm, a pulley spaced from said outer end and at least one inner pulley, a track section, a counterweight, a flexible member connected to 10 said track section and to said counterweight and trained over said pulleys, and a stop member for limiting the upward movement of said track section.

2. The combination of claim 1 which includes 15 a means for guiding the upward and downward movement of the track section.

3. In apparatus of the class described, a candle 20 carrying frame, means for raising and lowering said candle carrying frame, a hot-plate mounted underneath said frame, said hot-plate having a double serrated top surface whereby when the candle frame is lowered to melt excessive wax from the base of the candles each candle will 25 maintain a vertical position and will not slide on the surface of the hot-plate.

4. In apparatus of the class described, a frame, 30 means for suspending candles from said frame, a hot-plate located beneath said frame, said hot-plate having its upper surface scored, and means for causing relative vertical movement between said frame and said hot-plate whereby the lower ends of said candles may contact with the scored surface of said hot-plate to melt away excessive material from the base of the candles.

5. The combination defined in claim 1 including 35 a stationary track located adjacent to said wheel in a plane common to the plane of said track section when the track section is at the limits of its upward movement, and means oper-

able at will for establishing track connection be-

tween said stationary track and said track section.

6. The combination defined in claim 1 including 5 a stationary track located adjacent to the wheel in a plane common to the plane of said track section when the track section is at the limit of its upward movement, means operable at will for establishing track connection between said stationary track and said track section, and a plurality of carriages movable upon said track 10 and track section.

7. The combination defined in claim 1 including 15 a stationary endless track located adjacent to said wheel and on a level with said track section when said track section is at the limit of its upward movement, switch means operable at will for establishing track connection between said stationary track and said track section when the track section is elevated, and a plurality of carriages 20 movable upon said track and track section whereby carriages from the track may be raised and lowered at will when moved upon said track section.

8. The combination defined in claim 1 including 25 a stationary track located adjacent to said wheel and level with said track section when said track section is at the limit of its upward movement, carriages movable upon said track and track section, said carriages including trains for suspending articles to be treated therefrom, a plurality of treating process stations located under said wheel and under said stationary track and means operable at will for establishing track connection between said stationary track 30 and said track section whereby the carriages having articles suspended therefrom may be moved in a horizontal plane along said stationary track and in a vertical plane when on said track section.

CARL J. SCHROEDER. 40
